[57] CLAIM

The ornamental design for a cash register, as shown and described.

DESCRIPTION

FIG. 1 is a perspective view of a cash register showing our new design;

FIG. 2 is a front view of the cash register shown in FIG. 1;

FIG. 3 is a rear view of the cash register shown in FIG. 1;

FIG. 4 is a left side view of the cash register shown in FIG. 1;

FIG. 5 is a right side view of the cash register shown in FIG. 1;

FIG. 6 is a top view of the cash register shown in FIG. 1;

FIG. 7 is a bottom view of the cash register shown in FIG. 1;

FIG. 8 is a perspective view of a second embodiment of our new design of FIGS. 1-7;

FIG. 9 is a front view of the cash register shown in FIG. 8;

FIG. 10 is a rear view of the cash register shown in FIG. 8;

FIG. 11 is a left side view of the cash register shown in FIG. 8;

FIG. 12 is a right side view of the cash register shown in FIG. 8;

FIG. 13 is a top view of the cash register shown in FIG. 8;

FIG. 14 is a bottom view of the cash register shown in FIG. 8;

FIG. 15 is a perspective view of a third embodiment of our new design of FIGS. 1-7;

FIG. 16 is a front view of the cash register shown in FIG. 15;

FIG. 17 is a rear view of the cash register shown in FIG. 15;

FIG. 18 is a left side view of the cash register shown in FIG. 15;

FIG. 19 is a right side view of the cash register shown in FIG. 15;

FIG. 20 is a top view of the cash register shown in FIG. 15; and,

FIG. 21 is a bottom view of the cash register shown in FIG. 15.

FIG. 1
